UNITED STATES PATENT OFFICE.

HENRY GEORGE HILLMAN, OF NEW YORK, N. Y.

ELEVATOR SAFETY DEVICE.

Application filed April 8, 1922. Serial No. 550,756.

To all whom it may concern:

Be it known that I, HENRY GEORGE HILLMAN, a citizen of the United States, and a resident of the city of New York, borough of Manhattan, in the county and State of New York, have invented a new and Improved Elevator Safety Device, of which the following is a full, clear, and exact description.

10 This invention relates to an elevator safety device, and has for an object the provision of a simple, efficient, durable device which is automatically operated whenever a door leading into the elevator shaftway, or the 15 collapsible gate on the elevator cage, is opened to lock the controlling mechanism of the car.

Another object resides in the provision of means whereby whenever a door is opened, either on the elevator car or in the shaftway, the operating mechanism under the 20 manual control of the operator in the car will be locked to prevent the operator from moving the car without full knowledge of 25 the dangerous condition existing, and also gives the elevator operator instant notice whenever the elevator door safety system is not in perfect condition.

A further object resides in the particular 30 construction and arrangement of parts which are hereinafter described and claimed and shown in the accompanying drawings.

The invention is illustrated in the drawings, of which—

35 Figure 1 is a diagrammatic elevation of one form of the invention.

Fig. 2 is a side elevation of a modified application of the invention shown in Fig. 1.

The forms of the invention shown in the 40 drawings are preferred forms, although it is understood that modifications in the construction and arrangement of the parts and in the character of the materials used may be adopted without departing from the spirit 45 of the invention.

The preferred forms of the invention illustrated in the drawings are applicable to an elevator in which the control of power thereto is regulated by means of a control wheel 1. This wheel is provided with a pair of 50 adjustable plates 2 and 3 of the type shown in United States Patent No. 981,442, entitled "Elevator devices", issued to Robert P. Lumley and Henry G. Hillman on January 10, 55 1911.

This control wheel 1 may be one which

controls electrical power to drive the elevator, or hydraulic power. The plates 2 and 3 are disposed apart a definite distance and in the spaces between these plates the ends 60 of a pair of pivoted pawls 4 and 5 are adapted under certain conditions to lie and limit the movement permissible to the wheel 1 in either direction. These pawls are pivoted to any suitable stationary frame 6 and 65 the weight of the pawls is so distributed around their pivot points that the pawls tend of themselves to drop into place between the plates 2 and 3. The rear or other ends of the pawls are adapted to be engaged by a 70 weight 7 mounted to slide vertically on rods 8 and 9. This weight is connected by a stem 10 to one end of a lever 11 pivoted at 12 on a standard 13. The other end 14 of this lever is adapted to be engaged by an 75 armature 15 pivoted at 16 on a standard 17 mounted on a frame or base 18 connected to the stationary frame 6 previously mentioned. This armature is adapted to be attracted by an electro-magnet 19 and the attraction of the armature results in the depression of the end 14 of the lever 11 so that the other end to which the weight 7 is connected is elevated thereby elevating the 80 weight from engagement with the pawls 4 and 5 to permit them by reason of their weight to drop into place to lock the control device or wheel 1. In other words, it is noted that the weight normally acts by gravity to bear against the pawls 4 and 90 5 to hold them out of engagement or out of the path of the plates 2 and 3 so that the control device 1 can be freely actuated in one manner or another. The magnet 19 is 95 connected by a wire 20 to one or more switches such as 21 which are normally open and are adapted to be closed whenever a door in the elevator itself or in the elevator shaftway or other closure, such as a gate, is opened. The other side of the magnet is 100 connected by wire 22 to a release switch 23 which is disposed in the elevator car and is normally closed but which when pressed will open the circuit in which it is disposed. A suitable source of power is connected 105 through switch 24 from wires 25 and 26 into the circuit of the electro-magnet. The switches 21 are also connected by a wire 27 to the emergency release switch 23.

A light or signal or indicating device 28 110 is disposed in the car and connected on one side by a wire 29 to a fixed contact member

30 mounted in any suitable manner on the support 6. This contact member is adapted to co-operate with another contact member 31 attached to and movable with the armature 15. The contact member 31 is connected by a wire 32 to one side of the electro-magnet 19, and the circuit for the contact members and the wire 29 can be traced through this electro-magnet 19, through wire 22, through the release switch 23, back to the other side of the light 28. It will be observed, therefore, that whenever a door is open the circuit through the electro-magnet 19 is closed. This causes the depression 15 of the armature 15 and by the mechanism above referred to, the elevation of the weight 7 releases the pawls or fingers 4 and 5 which immediately drop into place between the plates 2 and 3. If these plates are not quite 20 in the exact position shown in Fig. 1, one of the pawls 4 and 5 will engage with teeth such as 33 on the respective plates to limit the motion of the control device in any direction, excepting that it will restore it 25 to its closed or inoperative position in which no power application is possible. When a door has been opened and this locking action takes place, it will be noticed that the emergency release switch 23 can be depressed by 30 the operator to open the circuit of the magnet 19, thus permitting the weight 7 to drop and allow freedom of movement to the control wheel 1. This release of the wheel or control member 1 cannot, however, take 35 place except by the deliberate action of the operator after he has found that he cannot move his control member and has been warned by the illumination of the signal or light 28.

40 The release of the pawls 4 and 5 is effected in a very simple and a substantially automatic manner by reason of the lifting of the weight 7. For this reason the normally open circuit system is used. This system is one of the type shown in my United States Patent No. 1,171,338, entitled "Safety device", issued February 8, 1916; and the indicating device is of the type set forth in my United States Patent No. 1,244,211, entitled "Elevator safety system", issued October 23, 1917.

45 In Fig. 2 is shown the weight 7, the pawls 4 and 5 associated with plates 2 and 3, the armature 15, the lever 11, and the magnet 19. The plates 2 and 3 in this case, however, are mounted on an operating rod or bar 34 moved by a hand lever 35 under the manual control of the operator within the elevator. This bar is adapted to alter the disposition 50 of the cable sheaves or pulleys 36 and thus

effect, in a well known manner, the application of power to the elevator system. The engagement of the pawls 4 and 5 with the plates 2 and 3 in this instance, however, is effected in the same manner as that previously described, and the operation in all other respects is the same. 65

What I claim is:

1. An elevator safety device which comprises a control member responsive to the actuation of the elevator operator, a pawl having a normal tendency to engage the control member and limit its movement, means responsive to gravity normally engaging the pawl to hold it disengaged from the control member, an electro-magnet energized over a suitable circuit when any door is open, and means actuated by the energization of the electro-magnet to release the gravity-responsive means from the pawl whereby the pawl is permitted to respond to its normal tendency to engage the control member to limit its movement. 70 75

2. An elevator safety device which comprises a control wheel, a pair of pawls having a normal tendency to engage the control member, means on the control member with which the pawl is engaged to limit the movement of the control member, a weight associated with the pawl and responsive to gravity normally to hold the pawl disengaged from the control wheel, a lever connected to the weight, an electro-magnet energized whenever a door is open, and an armature actuated by the energization of the electro-magnet, said armature actuating the lever to lift the weight from the pawl whereby the pawl will engage the wheel to limit its movement. 80 85 90

3. A safety device for elevators having a control member, a magnet, door-operating switches and circuits connecting the switches with the magnet, said magnet adapted to be operated when a door is opened, said devices comprising pivoted members normally tending by reason of their balance in response to gravity to engage the control member and lock it in an inoperative position, a slidable member responsive to gravity and adapted normally to hold said pivoted members in their disengaged position, and means associating the slidable member with the magnet whereby when the magnet is energized the slidable member will be released from the pivoted members whereby said pivoted members will drop into their normal position of engagement with the control member. 100 105 110 115

HENRY GEORGE HILLMAN.
